UNITED STATES PATENT OFFICE.

HIRAM PERCY MAXIM, OF HARTFORD, CONNECTICUT.

DESIGN FOR A RUNNING-GEAR FRAME.

SPECIFICATION forming part of Design No. 27,663, dated September 21, 1897.

Application filed August 6, 1897. Serial No. 647,379. Term of patent 14 years.

To all whom it may concern:

Be it known that I, HIRAM PERCY MAXIM, a citizen of the United States, residing in the city and county of Hartford, State of Connecticut, have invented a certain new and original Design for a Running-Gear Frame, of which the following is a specification, reference being had to the accompanying drawings, forming a part hereof.

10 This invention relates to that portion of a vehicle which is intermediate the wheels and the body and is generally known as the "running-gear frame," and it consists in the novel form or shape therefor, as herein set forth.

15 In the accompanying drawings, Figure 1 represents in perspective view, as seen from above, a running-gear frame which embodies my design. Fig. 2 is a view in side elevation of the frame shown in Fig. 1, and Fig. 3 is a 20 view in end elevation of the same.

As seen in side elevation, the frame presents

to the eye two bars *a* and *b*, which are arched upward somewhat and are crossed at intervals by bands *c c*. The end portions of the lower bar *b* curve downwardly away from the 25 bar *a* and are joined, respectively, to a pendant *d* from one extremity of the bar *a* and a pendant *e* from the other extremity. The pendant *e* is longer than the pendant *d* and extends below the point of union with the 30 bar *b*. The front portion *f*, between the pendants *e e*, presents to the eye an inverted arch of large radius.

I claim as my invention—

The design for a running-gear frame for a 35 vehicle, substantially as shown and described.

This specification signed and witnessed this 3d day of August, A. D. 1897.

HIRAM PERCY MAXIM.

In presence of—

JAMES G. EAMES,
FELTON PARKER.
